INVENTOR

Daniel Pike.

United States Patent Office.

DANIEL PIKE, OF NEW ORLEANS, LOUISIANA, ASSIGNOR TO HIMSELF, JOSHUA E. VOSE, AND W. J. McCULLOH, OF SAME PLACE.

Letters Patent No. 91,663, dated June 22, 1869.

IMPROVED RAILWAY-SWITCHING APPARATUS.

The Schedule referred to in these Letters Patent and making part of the same.

To all whom it may concern:

Be it known that I, DANIEL PIKE, of the city of New Orleans, parish of Orleans, and State of Louisiana, have invented a certain new, useful, and improved Apparatus for Switching Railroad-Cars into Branch or Divergent Tracks; and I do hereby declare the following to be a full, clear, and exact description of the same, reference being had to the annexed drawing, making a part of this specification, in which—

Figure 1 is a perspective view of the running gear and floor of a car, with my apparatus attached thereto, and

Figure 2, a bottom view of the same.

The importance of having an apparatus on the cars of city-railroads, by which said cars may be switched into diverging tracks by the drivers, and thus to render the keeping of a switch-tender at every intersection of two or more tracks unnecessary, has long been fully felt and appreciated by the owners and managers of such roads; for it is not only expensive to provide switch-tenders, but it has been shown by experience that it is impossible to procure men for this purpose who will be constantly alert in the discharge of their duty, and that hence cars are frequently run upon the wrong track in passing an intersection, by reason of their failure to move the switch at the proper time.

When this happens, the car must be pushed back by hand, oftentimes with difficulty, and after much delay, not only to the car to which the accident has occurred, but to all the others that have, meanwhile, come up.

It sometimes happens, in fact, that the whole arrangement of a city-railroad, with respect to the time of starting and running the cars on it, is, for a considerable period, at least, completely interrupted, in consequence of the non or improper operation of the switch by the switch-tender, and the running of a car on the wrong track.

My invention is designed to remedy all these evils; and

It consists of an apparatus that is attached to, and therefore carried upon the car, and operated by the driver.

It is, moreover, very simple, of easy operation, and can be applied to any existing car, whatever may be its form or peculiarities of construction.

I proceed now to describe its construction and operation, with reference to the drawing, in which the same letters denote the same parts at all the figures.

A is a strong pendent-strap metallic bracket, that is fastened, by means of bolts 1, 2, 3, 4, underneath the front extension of the floor of the car, that is commonly called the platform, near the front edge thereof, in order that it may be as far ahead of the fore axle and wheels of the car as possible.

The formation of this bracket is such that no lateral yielding can possibly take place, whilst the diagonal cross-braces B B' hold it immovably against any longitudinal or oblique strain or pressure to which it may be subjected.

A rod, C, passes perpendicularly through the platform of the car, and the centre of the horizontal section or part of the bracket A, proper apertures being provided for the purpose, as clearly shown at fig. 1.

At its lower extremity, the rod C is bifurcated, in order to receive the flanged pulley, or wheel D, between the jaws, or arms a b.

To enable the driver to operate the rod C readily, and with comfort to his foot, its length is calculated with reference to the height to which he may conveniently raise the same, and a cap, e, is fixed upon its upper end.

To reinforce the floor of the platform where the rod C passes through it, a metal plate, G, is provided, of any suitable form.

To hold the rod up whenever it is not pressed down by the foot of the driver to switch his car, a spring, E, is secured thereto, at one of its ends, at the point marked 6, whilst its other end is fastened to the floor of the car, by a screw or screw-bolt, 5.

This spring is so arranged, as always to keep the enlarged part of the rod C, resulting from its division into the jaws a b, in contact with the bracket A, and, therefore, at its highest possible point of elevation, excepting when it is purposely pressed down.

In the use of my apparatus, a short bar, F, is necessary to its operation.

This bar is placed midway between the rails of the track, so as to overlap the intersection in both directions, and it is curved in such manner as to be precisely parallel to the rails of the intersecting or branch road, into which its function is, in connection with my apparatus, to switch the car.

This bar, in fact, is formed and placed about as shown on the drawing, and an inspection of the drawing will at once indicate the part performed by it in the practice or actual use of my invention; for, if we suppose that the car there delineated is to be taken, for example, upon the diverging-branch track H, it will be perceived that all that is necessary to effect that object is, for the driver to put his foot on the cap e, and press down the rod C until the flanch on wheel D comes in contact with bar F, as shown at fig. 1, when the lateral pressure against said flanch, which is induced by the curvature of the said bar, will force the car into the said track.

The moment the fore wheels pass the intersection, the driver releases the bar C, which is instantly thrown up, by the action of the spring E, into its normal position of elevation.

I am aware that it is not new to attempt the switching of railroad-cars, through the agency of mechanical arrangements connected to and carried on the same, and operated by the drivers; and hence I do not wish to be understood as broadly claiming to be the originator of such an arrangement; but, having fully described my invention,

What I claim, and desire to secure by Letters Patent, is—

The bracket A, when supported by the cross-braces

B B', in combination with the rod C, when constructed as herein described, and provided with the flanged wheel D, and sustained, at its highest point of elevation, by the spring E, substantially as and for the purpose herein set forth.

DANIEL PIKE.
